UNITED STATES PATENT OFFICE.

WILLIAM H. LUTTON, OF JERSEY CITY, NEW JERSEY.

GREENHOUSE CONSTRUCTION.

No. 902,155.

Specification of Letters Patent.

Patented Oct. 27, 1908.

Application filed April 27, 1908. Serial No. 429,850.

To all whom it may concern:

Be it known that I, WILLIAM H. LUTTON, a citizen of the United States, and residing at Jersey City, in the county of Hudson and State of New Jersey, have invented certain new and useful Improvements in Greenhouse Constructions, of which the following is a specification, such as will enable those skilled in the art to which it appertains to make and use the same.

This invention relates to the construction of greenhouses, and particularly to the roof and side wall construction; and the object of the invention is to provide an improved construction of this class whereby the eaves will be given a continuous curve so as to prevent snow, ice, sleet or other substances from collecting thereon.

The invention is fully disclosed in the following specification, of which the accompanying drawing forms a part, in which the separate parts of my improvement are designated by suitable reference characters in each of the views, and in which:—

Figure 1 is a sectional end view of one side portion of a greenhouse and showing my construction, Fig. 2 a perspective view of a metal the greenhouse, Fig. 3 a side view of a curve piece employed in connection with the bracket or support shown in Fig. 2 in order to form a continuous curve at the eaves between the rafters and the side posts or bars, and;— Fig. 4 a cross section on the line 4—4 of Fig. 1.

In the drawing forming part of this specification, I have shown one side portion of a greenhouse together with one side wall *a* and end wall *a*², Fig. 1 being an interior view, and I have also shown at *b* one of the side posts or bars and at *c* one of the rafters, and in the practice of my invention I form at *d* a continuous segmental curve between the rafter *c* and the post or side bar *b*.

It will be understood, that in practice, the side and side roof of the greenhouse above the wall *a* is made up of a plurality of the side posts of bars *b*, and the plurality of the rafters *c* equally spaced, and these side bars or posts are connected at the tops thereof by longitudinal angle bars *c*, and the rafters *c* are also connected by longitudinal angle bars *f*, and the form of the rafters *c* in cross section is shown in Fig. 4, and the space between the rafters is filled in with transparent panels *g* in the usual manner, and the rafters *c* are provided with side grooves *c*²

by means of which the water of condensation is carried down to the sides of the house.

In forming the eave curve at *d* I provide segmental metal supports *h* provided at their opposite ends with outwardly directed ears *h*² between which the tops of the side bars or posts *b* and the lower ends of the rafters *c* are secured, and the upper ends of the bars or posts *b* and the lower ends of the rafters *c* are cut off at an inclination, as shown at *i*, and placed in the segmental metal supports *h* are segmentally curved pieces *j* which are similar in cross section to the rafters *c* and between which are placed transparent panels *k*, and the curved supports *h* are provided centrally with side ears *h*³ which aid in holding the parts *j* in position, and screws *m* are passed through the angle bars *f* and through the ends of the rafters *c* and the corresponding ends of the parts *j*, and also through the upper ends of the posts or side bars *b* and the corresponding ends of the parts *k*, and other screws *n* are passed centrally through the parts *h* into the members *j*.

In order to provide the curve *d* by the construction shown, the rafters *c*, side posts or bars *b* and parts *j* are composed of separate pieces; but it is possible to make these parts of a single piece, and bend said piece so as to produce the desired curve at *d*, and in this case the curved or segmental support *h* will be employed to hold the eave portions of the rafters *c* and posts or bars *b* in proper position and to maintain a proper curve.

It will be understood that the rafters *c* and side posts or bars *b* and the parts *j* are composed of wood, but the horizontal angle bars *f* which connect said parts longitudinally are composed of metal and the end frames of the greenhouse above the walls *a* and *a*² may be of the usual or any preferred construction, but are preferably provided at the sides and tops with reinforcing bars or posts.

By making the eaves curved as shown at *d*, I provide means whereby snow, ice, sleet and the like will not collect at the eaves as is customary with ordinary greenhouse construction, and all water or rain caused by melting snow, sleet, or ice will run rapidly off of the roof and over the eaves.

My invention is not limited to the exact details of construction herein shown and described, and various changes therein and modifications thereof may be made, within

the scope of the appended claims, without departing from the spirit of my invention or sacrificing its advantages.

Having fully described my invention, what I claim as new and desire to secure by Letters Patent, is:—

1. The herein described means for forming a curved eave construction for greenhouses provided with the usual rafters and side posts or bars, comprising separate curved segmental metal brackets or supports secured to the lower ends of the rafters and to the tops of the side bars or supports, and curved segmental pieces of wood secured to said brackets or supports and forming a continuation of the rafters and connecting the same with the tops of the side bars or posts.

2. The herein described means for forming a curved eave construction for greenhouses provided with the usual rafters and side posts or bars, comprising separate curved segmental metal brackets or supports se-

cured to the lower ends of the rafters and to the tops of the side bars or supports, and curved segmental pieces of wood secured to 25 said brackets or supports and forming a continuation of the rafters and connecting the same with the tops of the side bars or posts, and transparent panels placed between said curved segmental members.

3. In an eave construction for greenhouses, a curved segmental bracket provided at its opposite ends with outwardly directed ears h^2 , and between said ends with outwardly directed ears h^3 , and a curved segmental member secured to said bracket.

In testimony that I claim the foregoing as my invention I have signed my name in presence of the subscribing witnesses this 24th day of April, 1908.

WILLIAM H. LUTTON.
